UNITED STATES PATENT OFFICE.

ROBERT DELAUNAY-BELLEVILLE, OF ST. DENIS, FRANCE, ASSIGNOR TO SOCIETE ANONYME DES ETABLISSEMENTS DELAUNAY-BELLEVILLE, OF ST. DENIS, FRANCE, A CORPORATION OF FRANCE.

WATER-TUBE BOILER.

1,109,627.

Specification of Letters Patent.

Patented Sept. 1, 1914.

Application filed December 11, 1913. Serial No. 806,044.

To all whom it may concern:

Be it known that I, ROBERT DELAUNAY-BELLEVILLE, citizen of the French Republic, residing at St. Denis, Department of the Seine, in France, have invented certain new and useful Improvements in Water-Tube Boilers; and I do hereby declare the following to be a full, clear, and exact description of the invention, such as will enable others skilled in the art to which it appertains to make and use the same.

The present invention relates to boilers, and has for its object to provide an improved boiler element of the Belleville type.

The invention consists in composing each element of a spiral coil having clockwise convolutions and a spiral coil having anti-clockwise convolutions and also in mounting the junction boxes of the boiler tubes in staggered relation.

The invention is illustrated in the accompanying drawings, in which:—

Figure 1 shows the element in side elevation. Fig. 2 is a front elevation of the element showing the front boxes superposed in horizontal position. Fig. 3 is a front elevation showing the rear boxes projected in a vertical plane. Fig. 4 is a section on the line X—X in Fig. 1.

In the form of construction shown in the drawings, the elements consist of two spiral coils, one of which has clockwise convolutions and the other has anti-clockwise convolutions.

The front boxes are designated by the letter A for the spiral having clockwise convolutions with an index indicating the tier of the box in the spiral proceeding from below upward. The front boxes of the spiral having anti-clockwise convolutions are designated by the letter B with an index indicating the tier of the box in the spiral.

The rear boxes are designated by AR with an index for the spiral having clockwise convolutions and by BR with index for the spiral having anti-clockwise convolutions.

The tubes are designated by the letters *a* and *b* with an index indicating the tier of the tube in each of the spirals from below upward.

In order not to confuse the drawings, the reference letters have only been placed upon the spiral having clockwise convolutions of one element and upon the spiral having anti-

clockwise convolutions of the other element; 55 the tubes of the two other spirals are marked with a dot for the spiral having clockwise convolutions and with a cross for the spiral having anti-clockwise convolutions.

In Fig. 4, the broken lines indicate the 60 circulation paths in the spirals A and B; the horizontal portions of these lines represent the paths in the boxes; the vertical portions represent the paths in the tubes in rising from the first front box to the first 65 rear box, then from the first rear box to the second front box, then from the second front box to the second rear box and so on in succession.

For the spiral having clockwise convolutions, the first tube *a*¹ proceeds from the 70 front box A¹ (Fig. 2) which is in communication with the feed collector; this tube rises from the front toward the rear and is fixed to the right of the box AR¹ (Fig. 3) 75 the tube passes from right to left in the box AR¹, rises toward the front and is fixed on the left of the box A²; the current traverses this box from left to right. The tube *a*³ proceeds from the right of the box A² 80 rises toward the rear and is fixed to the right of the box AR²; the current traverses this box from right to left. The tube *a*⁴ proceeds from the right of the box AR², rising toward the front and is fixed to the 85 left of the box A³ and so on in succession; the tube *a*⁵ connects the right of the box A³ with the right of the box AR³; the tube *a*⁶ connects the left of the box AR³ with the box A⁴ which communicates with the steam 90 purifying collector.

The order is similar to the above for the spiral having anti-clockwise convolutions, the only difference between the two being that the paths for the current in the boxes 95 are in opposite directions. In the boxes of the spiral having clockwise convolutions, the current is from left to right in the front and from right to left at the rear; in the boxes of the spiral having anti-clockwise convolutions, the current is from right to left in the front box and from left to right in the rear boxes.

In Figs. 2 and 3 the small arrows indicate the direction of the current in the boxes. 105

The tube *b*¹ proceeds from the box B¹ which is in communication with the feed collector; this tube proceeds to the rear and

is fixed to the left of the box BR¹; the tube b² proceeds from the right of the box BR¹ passes to the front and is fixed to the right of the box B²; the tube b³ proceeds from the left of the box B², proceeds to the rear and is fixed to the left of the box BR²; the tube b⁴ proceeds from the right of the box BR², passes to the front and is fixed to the right of the box B³; the tube b⁵ proceeds from the left of the box B³ proceeds to the rear and is fixed to the left of the box BR³; the tube b⁶ proceeds from the right of the box BR³ proceeds to the front and is fixed to the box B⁴ which is in communication with the steam purifying collector.

I claim:

A boiler element of the Belleville type, composed of a spiral coil having clockwise

convolutions and a spiral coil having anti-clockwise convolutions, the front boxes on the one hand and the rear boxes on the other hand being superposed but disposed in staggered relation, the left hand half of the boxes of the second spiral coil resting upon the right hand half of the boxes of the first spiral coil and vice versa, all the tubes rising from front to rear on the one hand and all the tubes rising from rear to front on the other hand being parallel and equally spaced.

In testimony whereof I affix my signature, in presence of two witnesses.

ROBERT DELAUNAY-BELLEVILLE.

Witnesses:

HANSON C. COXE,
EMILE KLOH.
